DESIGN FOR FRINGE.

Design No. 12,847, dated April 4, 1882.

UNITED STATES PATENT OFFICE.

HENRY A. KEHRENBURG, OF PHILADELPHIA, PENNSYLVANIA, ASSIGNOR
TO THE FAIR HILL MANUFACTURING COMPANY, OF SAME PLACE.

DESIGN FOR FRINGE.

SPECIFICATION forming part of Design No. 12,847, dated April 4, 1882.

Application filed February 21, 1882. Term of patent 3½ years.

To all whom it may concern:

Be it known that I, HENRY A. KEHRENBURG, a citizen of the United States, residing in the city and county of Philadelphia, State of Pennsylvania, have invented and produced a new and original Design for Fringe, of which the following is a specification, reference being had to the accompanying photographic illustration, forming part thereof, and in which—

10. A represents a flat tape or gimp heading, to which are attached at intervals chenille pendants B and strands C, alternately arranged, said strands being knotted; but the knots may be omitted, if desired.

The pendants and strands may be of any desired color, plain, shaded, or striped, and made of cotton, silk, worsted, or linen.

If desired, the heading may be ornamented by a stripe or cord of uniform or different color.

I claim—

The design for fringe, consisting of a heading having pendants and strands alternately arranged, as above set forth.

H. A. KEHRENBURG.
